Des. 197,556
Patented Feb. 25, 1964

197,556

AUTOMOBILE CAMPER

Dan B. Coco, 2105 N. Elwood, Tulsa, Okla.

Filed Oct. 29, 1962, Ser. No. 72,283

Term of patent 7 years

(Cl. D14—3)

FIG. 2

FIG. 3

FIG. 4

FIG. 5

FIGURE 1 is a perspective view of an automobile camper showing my new design with the doors and side window in open position.

FIGURE 2 is a side elevational view with the doors in open position.

FIGURE 3 is a top plan view thereof.

FIGURE 4 is a front elevational view thereof.

FIGURE 5 is a rear elevational view thereof.

The automobile shown in broken lines in FIGURE 1 is included for illustrative purposes only. The side not shown is a mirror image of the side shown.

I claim:

The ornamental design for an automobile camper, substantially as shown and described.
